Attorney

UNITED STATES PATENT OFFICE

JAMES H. PINKSTON, OF TULSA, OKLAHOMA

MASSAGE DEVICE

Application filed March 21, 1932. Serial No. 600,342.

My invention relates to a massage device.

An important object of the invention is to provide a device of the above-mentioned character, which is of simplified construction, inexpensive to manufacture, and is highly convenient in use.

In the accompanying drawing forming a part of this specification, and in which like numerals are employed to designate like parts throughout the same,

Figure 1 is a side elevation of a device embodying my invention, parts being shown in central vertical section,

Figure 2 is a front end elevation of the device, parts omitted.

Figure 3 is a perspective view of a tubular shaft and associated elements, parts omitted.

In the drawing, wherein for the purpose of illustration is shown a preferred embodiment of my invention, the numeral 5 designates the casing of a motor, of any well known and preferred construction. This motor includes an armature shaft, 6, carrying the usual armature, not shown. The rear end of this armature shaft is journaled in a bearing 7. The motor casing 5 is rigidly mounted upon a handle 8, and has its longitudinal axis disposed at a right angle to the longitudinal axis of the handle. The handle is preferably tubular for receiving the lead wires 9, extending to the motor, whereby current may be supplied thereto to drive the same, as is customary.

The motor casing 5 is circular in cross-section, and its forward side is open and is internally screw-threaded for receiving an externally screw-threaded extension 10, of a coupling ring 11. This coupling ring is included in a spider comprising radial arms or spokes 12, rigidly secured thereto, and rigidly secured to a hub or bearing 13, which receives the forward portion of the armature shaft 6, as shown. The outer coupling ring 14, surrounds the inner coupling ring 10, in spaced concentric relation, and is rigidly attached thereto by spaced radial elements or webs 15, affording passages 16. These passages are arranged to discharge air rearwardly over the motor casing 5, thereby serving to cool the same.

The numeral 17 designates a shield, which is circular in cross-section, and tapers forwardly. This shield embodies a rear shield section 18, tapering forwardly, and having its rear large end mounted upon the outer coupling ring 14, and having screw-threaded engagement therewith. The shield further comprises a forward shield section 19, which tapers forwardly, and has its large rear end telescoping with the forward reduced end of the shield section 18, and having screw-threaded engagement therewith, as shown.

The numeral 20 designates a flexible resilient vacuum cup, formed of rubber or other suitable material, and this vacuum cup has its rear end arranged within a recess 21, formed in the forward end of the shield section 19, and clamped therein by a sleeve 22, arranged interiorly of the forward end of the shield section 19 and having screw-threaded engagement therewith.

The numeral 23 designates a rotary disc, constituting the body portion of a fan element. This rotary disc has a rearwardly projecting annular flange 24, operating in cross relation to the inner coupling ring 11, and preferably slidably contacting therewith. This rotary disc closes the inner side of a passage 25, the outer side of which is defined by the shield 18. Preferably formed integral with the forward side of the rotary disc 23 are longitudinally curved generally radial vanes 26, spaced as shown, for providing air passages 27. The disc 23 is formed integral with a tubular hub 28, which is clamped to the armature shaft 6, by a set screw 29, or the like. The hub 28 is provided with a sleeve 30, as shown.

The numeral 31 designates a tubular shaft, which is slidably mounted upon the forward end of the armature shaft 6, and has longitudinal slots 32, receiving a transverse pin 33, which limits the relative longitudinal movement of the tubular shaft. Disposed at the forward end of the tubular shaft is a massage element 34, formed of rubber, or the like, having a desired degree of stiffness and resiliency. This massage element is suitably attached to a cup shaped back 35, which may have screw-threaded engagement

with the forward end of the tubular shaft 31, and is clamped to this shaft by a ring nut 36, having screw-threaded engagement with the tubular shaft. This ring nut is engaged by a compressible coil spring 37, which surrounds the tubular shaft 31 in spaced relation. The rear end of the spring 37 is arranged upon the stationary sleeve 30, and engages within a recess formed in a ring 38, which is suitably clamped to the sleeve 30.

From the foregoing description, it will be seen that the tubular shaft 31 is rotatable with the armature shaft 6, and is capable of moving longitudinally with relation thereto.

The operation of the device is as follows:

When the motor is driven, the armature shaft 6 is rotated and the fan element rotated. The vanes 26 of the fan element throw currents of air outwardly which travels through the passage 25 and discharge rearwardly to the atmosphere around the motor casing 5. A suction of vacuum is, therefore, created within the vacuum cup 20, which may now be applied to the desired portion of the body. When this is done, the rotating massage element 34 is brought into proper contact with the body, to massage the same, in the presence of a vacuum or suction. The spring 37 permits of the proper rearward movement of the massage element, when desired.

It is to be understood that the form of my invention herewith shown and described is to be taken as the preferred example of the same, and that various changes in the shape, size and arrangement of parts may be resorted to without departing from the spirit of the invention or the scope of the subjoined claims.

Having thus described my invention, what I claim is:

1. A massage device comprising a motor, including a casing and armature shaft extending longitudinally of the casing, one end of the casing being open, a handle secured to the motor casing and having its longitudinal axis extending transversely of the longitudinal axis of the motor casing, a spider including a coupling ring secured to the open end of the motor casing, a hub bearing for receiving the armature shaft, spaced elements connecting the coupling ring and the hub bearing, an outer coupling ring surrounding the first-named coupling ring in spaced relation thereto and connected therewith, a forwardly tapering shield having its large rear end secured to the outer coupling ring, a fan element embodying a disc mounted upon the armature shaft for rotation therewith and coacting with the shield to provide an air passage, said disc having

generally radial vanes, a vacuum cup secured to the forward end of the shield, and a massage element connected with the armature shaft and arranged within the vacuum cup.

2. A massage device comprising a motor including a casing and an armature shaft extending longitudinally of the casing, one end of the casing being open, a handle secured to the motor casing, a spider including a coupling ring secured to the open end of the motor casing, a hub bearing for receiving the armature shaft, spaced elements connecting the coupling ring and hub bearing, an outer coupling ring surrounding the first-named coupling ring in spaced relation thereto and connected therewith, a forwardly tapering shield having its large end secured to the outer coupling ring, a fan element embodying a disc mounted upon the armature shaft and co-acting with the shield to provide an air passage, said disc having generally radial vanes, a vacuum cup secured to the forward end of the shield, and a massage element connected with the armature shaft and arranged within the vacuum cup.

3. A massage device comprising a motor including a casing and an armature shaft extending longitudinally within the casing, an attaching unit comprising a coupling ring secured to the casing, a hub bearing carried by the coupling ring for receiving the armature shaft, an outer coupling ring surrounding the first-named coupling ring in spaced relation thereto and connected therewith in a manner for affording air passages between the same, a shield having its rear end secured to the outer coupling ring, a fan element embodying a disc mounted upon the armature shaft and coacting with the shield to provide an air passage, said disc having generally radial vanes, a vacuum cup secured to the forward end of the shield, and a massage element connected with the armature shaft and arranged within the vacuum cup.

4. A massage device comprising a motor including a casing and an armature shaft extending longitudinally of the casing, a connecting unit including a coupling ring secured to the casing and a hub bearing for receiving the armature shaft, an outer coupling ring surrounding the first-named coupling ring in spaced relation, means connecting the first-named coupling ring and outer coupling ring for affording air passages between the same, a shield having one end secured to the outer coupling ring, a fan element mounted upon the armature shaft and disposed within the shield, a vacuum cup secured to the forward end of the shield, and a massage element connected with the armature shaft and arranged within the vacuum cup.

JAMES H. PINKSTON.
